UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

LOCK MECHANISM OF BREECH-LOADING GUNS.

1,116,026.

Specification of Letters Patent.

Patented Nov. 3, 1914.

Application filed January 26, 1914. Serial No. 814,540.

To all whom it may concern:

Be it known that we, ARTHUR TREVOR DAWSON, knight, and GEORGE THOMAS BUCKHAM, both subjects of the King of Great Britain, residing at Vickers House, Broadway, Westminster, in the county of London, England, have invented certain new and useful improvements in or Relating to the Lock Mechanism of Breech-Loading 5 Guns, of which the following is a specification.

This invention relates to lock mechanism of the kind having a re-priming device that comprises a primer magazine and a bolt 15 which is carried by the laterally moving lock frame and is used for introducing a new primer from the magazine into the primer chamber of the vent axial.

According to this invention the primer magazine is in the form of a hopper carried by the lock frame and the primers therein are under the control of a device which permits the primers to escape from the hoppers one by one and which is also carried by the lock 25 frame and capable of being actuated either by means of a cam on the box slide during the lateral movement of the lock frame or by the mechanism employed for cocking the firing pin or striker of the bolt.

30 In order that the said invention may be clearly understood and readily carried into effect, we will describe the same more fully with reference to the accompanying drawings in which:—

35 Figures 1, 2 and 3 are transverse sections through the hopper showing a constructional form of our invention in which the device for controlling the primers is in the form of a cam on the box slide, Fig. 1 showing the position of the primers immediately prior to the insertion of the lowermost one into the primer chamber and Fig. 2 after this primer has been inserted, while Fig. 40 3 shows the position of the parts when the 45 magazine is empty. Figs. 4 and 5 are transverse sections showing a constructional form of the invention in which the device for controlling the primers is actuated by the mechanism employed for cocking the 50 firing pin of the bolt, these figures indicating the position of the parts respectively prior to and after the retraction of the bolt, and, Fig. 6 is a side elevation of Fig. 4. Figs. 7 and 8 are respectively a rear elevation 55 with a part in section and a sectional

plan of the mechanism for actuating the device of Figs. 4 and 5.

In all these figures A represents the hopper, B the bolt, C the device for controlling the movements of the primers, and D the lock frame carrying the hopper, the bolt and the said device.

The invention is, in all the examples illustrated, shown applied to the form of lock mechanism described in the specification of the prior U. S. Patent, No. 1,095,558.

In the construction illustrated by Figs. 1 to 3 wherein the aforesaid device is moved by a cam on the box slide, the device C is in the form of a lever pivoted at c to the lock 70 frame D carrying the hopper A, the upper end of which lever normally (i. e. when the lock frame is closed) lies in the path of the primers in the hopper. The lower end of the said lever is adapted to coöperate with a cam slot or groove E in the box slide during the opening movements of the lock frame, to permit one of the primers to escape from the hopper A and come to rest 75 upon the bolt sleeve. During the closing movement of the lock frame the cam slot or groove E causes the upper end of the said lever to engage with the under side of the primer that is situated immediately above the one resting on the bolt sleeve (Fig. 1).

When the bolt sleeve is retracted by the cocking handle C^a (Fig. 7) described in the above mentioned prior specification, the primer that is resting on the bolt sleeve falls into position in front of the bolt head 90 (Fig. 2) and is inserted into the vent axial when the bolt is moved forward by the cocking handle, the aforesaid lever preventing the primer that is now the lowermost one in the hopper from escaping. The hopper 95 may be provided with a contrivance for indicating when it is empty, this contrivance comprising as shown, a hinged plate or leaf A' which until the magazine is empty, lies hidden within a suitable cavity or recess A² (Figs. 1 and 2) but is under the control of a light spring and has a toe-piece a' arranged in the path of the primers in the hopper so that when the last of the primers escapes from the hopper, the spring moves the plate or leaf into a visible position (Fig. 3) to indicate that the hopper 100 should be re-charged.

In the construction illustrated by Figs. 4 to 6 in which the aforesaid device C is 110

adapted to be moved by the mechanism employed for cocking the firing pin or striker, the said device may be in the form of an escapement lever pivoted at *c* to the lock frame and connected to the aforesaid cocking handle *C*³ by a lever *C'* carried by the lock frame *D*, this lever *C'* engaging with a cam slot *C*⁴ formed in an arm *C*⁵ operated by the handle *C*³; this arm also has another slot *C*⁶ for operating the bolt. The escapement lever is normally (*i. e.* prior to the actuation of the cocking handle to retract the bolt) in the position shown in Fig. 4 and in full lines in Fig. 7 in which position the 15 lowermost primer is disposed between the arms of the said lever. Movement of the cocking handle in the direction indicated by the arrow in Fig. 7 retracts the bolt and displaces the escapement lever into the position shown in Fig. 5 and in broken lines in Fig. 7 in which position the lowermost primer is permitted to fall in front of the bolt head, and the next primer is prevented from escaping from the hopper. The movement 20 of the cocking handle in the direction to move the bolt forward displaces the escapement lever into the position shown in Fig. 4 and in full lines in Fig. 7 to permit the last mentioned primer in the hopper to 25 move into a position between the two arms of the escapement lever as aforesaid.

What we claim and desire to secure by Letters Patent of the United States is:—

1. In lock mechanism for ordnance, the combination with the bolt and lock frame, 35 of a primer magazine in the form of a hopper carried by the lock frame, a device independent of the bolt which permits the primers to escape from the hopper one by one and which is also carried by the lock 40 frame, and means for automatically displacing said device to enable the primers to escape one by one, to a position in front of the bolt-head.

2. In lock mechanism for ordnance, the 45 combination with the bolt, the lock-frame, and the primer magazine carried by the lock frame, of a lever independent of the bolt and adapted to permit the primers to escape from the magazine one by one, and 50 a stationary part having a cam groove adapted to actuate said lever during the opening and closing movements of the lock-frame.

In testimony whereof we affix our signatures in the presence of two witnesses.

ARTHUR TREVOR DAWSON.
GEORGE THOMAS BUCKHAM.
